US0D1077850S

(12) **United States Design Patent** (10) **Patent No.:** **US D1,077,850 S**
Manzoni (45) **Date of Patent:** **** Jun. 3, 2025**

(54) **DISPLAY SCREEN WITH GRAPHICAL USER INTERFACE**

(71) Applicant: **FERRARI S.p.A.**, Modena (IT)

(72) Inventor: **Flavio Manzoni**, Modena (IT)

(73) Assignee: **FERRARI S.p.A.**, Modena (IT)

(**) Term: **15 Years**

(21) Appl. No.: **29/984,665**

(22) Filed: **Jan. 15, 2025**

Related U.S. Application Data

(62) Division of application No. 35/520,976, filed on May 18, 2023 (U.S. filing date under 35 U.S.C. 384), and having an international filing date of May 18, 2023.

CLAIM

The ornamental design for a display screen with graphical user interface, as shown and described.

DESCRIPTION

The sole FIGURE is a front view of the display screen with graphical user interface showing my design.

Broken lines illustrate a steering wheel with the display screen and portions of the graphical user interface that form no part of the claimed design.

1 Claim, 1 Drawing Sheet
